(57) **CLAIM**

The ornamental design for a portable holding apparatus for bed sheets/comforters, as shown and described.

DESCRIPTION

FIG. 1 is a front elevational view of a portable holding apparatus for bed sheets/comforters showing our new design;

FIG. 2 is a rear elevational view thereof;

FIG. 3 is a side elevational view thereof;

FIG. 4 is a top plan view thereof; and,

FIG. 5 is a bottom plan view thereof.

In the drawings, the surface shading represents wood; the broken lines represent environmental structure forming no part of the claim.
